UNITED STATES PATENT OFFICE.

FREDERICK B. MORROW, OF SAN FRANCISCO, CALIFORNIA.

DESIGN FOR A METAL INGOT.

SPECIFICATION forming part of Design No. 16,762, dated June 29, 1886.

Application filed May 15, 1886. Serial No. 202,335. Term of patent 7 years.

To all whom it may concern:

Be it known that I, FREDERICK B. MORROW, a citizen of the United States, residing at the city and county of San Francisco, and State of California, have invented and produced a new and original Design for Metal Ingots, of which the following is a specification, reference being had to the accompanying drawing, forming part thereof.

10 My invention relates to a design for metal ingots, which will be more fully described by reference to the accompanying drawing, in which the figure is a perspective view of my design.

15 My design consists of a series of short cylinders or frustums of cones arising from a common base, by which they are united so as to stand in line.

A is the base, and B are the cylinders or 20 frustums of cones, which arise from it at short intervals, so as to resemble small inverted cups, the bottoms of which are flattened and may

have a raised bead or ridge, C, around the edge.

Having thus described my invention, what I 25 claim as new, and desire to secure by Letters Patent, is—

1. A design for metal ingots, consisting of the cylindrical and tapering blocks arising from a continuous uniting base, with spaces or 30 intervals between them, as shown and described.

2. A design for metal ingots, consisting of the cylindrical and tapering blocks projecting from a continuous uniting base, and having 35 flat bases with a raised rim or bead, as shown and described.

In witness whereof I have hereunto set my hand.

FREDERICK B. MORROW.
